UNITED STATES PATENT OFFICE.

THOMAS FARRINGTON AND LEWIS WHITE, OF WASHINGTON COUNTY,
VERMONT.

IMPROVED WRINGING-MACHINE.

Specification forming part of Letters Patent No. 37,284, dated January 6, 1863.

To all whom it may concern:

Be it known that we, THOMAS FARRINGTON and LEWIS WHITE, of the county of Washington, and State of Vermont, have invented certain new and useful Improvements in Wringing-Machines; and we do hereby declare that the following is a true and exact description of the same, reference being had to the accompanying drawings, and to the letters of reference marked thereon.

Figure 1 in the annexed drawings, which are made a part of this specification, represents a front elevation of our machine.

C C are the rubber rollers with iron spindles passing through them, the spindles having their bearings at the points a a, as exhibited in Fig. 2, which is an end view of the frame or body of the machine.

B is an iron rod binding the two ends of the frame together at the top. This rod passes through the slots c c at each end of the frame and through the spring marked A.

F F are thumb-screws at the top of the frame and immediately over the rod B, by the operation of which the rod B is forced down on the springs A A, and as one end of the springs rests on the adjustable bearings E E, the pressure of the upper on the lower roller may be increased to any degree required. The adjustable bearings E E play vertically on the bolt J, (seen in Fig. 2,) which pass through them and through the ends of the frame.

K is a knob, intended to support the spring A.

L represents one jaw of the clamp intended

to attach the machine to a tub, and is cast solid with the frame. M is the other jaw, made adjustable by means of the screw N, which passes through it and through L. On one end of N is a nut attached to the lever O, by which it is operated. The jaw M is made thin on the outer edge and thicker at the inner edge, so that when it embraces the tub only the inner edge will come in contact with it. The jaw L is made thickest at the outer edge and thin on the inner, thus making the two sides of the jaws parallel as they embrace the tub, the sharp angle of each holding the tub more firmly than clamps as commonly made.

R, as indicated by dotted lines, is a rod placed back of the lower roller and intended to assist in binding the two ends of the machine together.

P is the end of the spindle to which the crank is attached and by which the machine is operated.

Having thus accurately described our invention, what we claim and desire to secure by Letters Patent, is—

The thumb-screw F, the rod B; the slot c, the spring A, and the adjustable bearing E, arranged in the manner and for the purpose herein fully set forth and described.

THOMAS FARRINGTON.
LEWIS WHITE.
